DRINKING GLASS OR THE LIKE

Johannes Klober, Schwelm, Westphalia, Germany, assignor to Firma Hans Klober, Schwelm, Westphalia, Germany

Original design application Apr. 16, 1969, Ser. No. 16,765.
Divided and this application May 1, 1970, Ser. No. 22,755

Claims priority, application Germany Nov. 25, 1968

Term of patent 14 years

Int. Cl. D7—01

U.S. Cl. D36—8

The figure is a perspective view of a drinking glass or the like, showing my new design, the opposite side being substantially identical.

This is a division of my earlier application, D-16,765 of Apr. 16, 1969.

I claim:

The ornamental design for a drinking glass or the like, as shown and described.
